Primary Examiner — Carla J Wright

(57) **CLAIM**

The ornamental design for a phone case as shown and described.

DESCRIPTION

FIG. 1 is a front, left perspective view of a phone case showing a first embodiment of our new design;

FIG. 2 is a rear, right perspective view of FIG. 1;

FIG. 3 is a front view of FIG. 1;

FIG. 4 is a rear view of FIG. 1;

FIG. 5 is a left view of FIG. 1;

FIG. 6 is a right view of FIG. 1;

FIG. 7 is a top view of FIG. 1;

FIG. 8 is a bottom view of FIG. 1;

FIG. 9 is a front, left perspective view of a phone case showing a second embodiment of our new design;

FIG. 10 is rear, right perspective view of FIG. 9;

FIG. 11 is a front view of FIG. 9;

FIG. 12 is a rear view of FIG. 9;

FIG. 13 is a left view of FIG. 9;

FIG. 14 is a right view of FIG. 9;

FIG. 15 is a top view of FIG. 9; and,

FIG. 16 is a bottom view of FIG. 9.

The broken lines shown in the drawings depict portions of the phone case that form no part of the claimed design.
